Roswell Bush Rochester New York
Letters Patent (Design No 147) Dated Sept 4th 1847

W.W.

The schedule referred to in these Letters Patent and making part of the same

To all whom it may concern: Be it known that I Roswell Bush of the City of Rochester, County of Monroe, and State of New York, have invented or produced a new ornamental design for a stone plate, and I do hereby declare that the following is a full, clear and exact description of the same. Fig 1 elevation of stone plate drawn one fourth full size. Fig 2 is a full size section through the door from A to B, Fig 1. Fig 3 is a full size drawing of one of the ornaments represented. b. b. b. b. Fig 1.

What I claim as my invention or production, and desire to secure by Letters Patent is the ornamental design of stone plate as herein described and represented;
